UNITED STATES PATENT OFFICE

JEFFREY JOHN WALLACE, OF AMITE, LOUISIANA, ASSIGNOR TO GULLETT GIN COMPANY, OF AMITE, LOUISIANA

BREAST LIFT

Original application filed May 6, 1931, Serial No. 535,523. Divided and this application filed May 20, 1932. Serial No. 612,804.

This application is a division of my co-pending application, Serial No. 535,523, filed May 6, 1931, for cotton gin.

The object of the invention to which the present application is limited is to provide a breast lift for cotton gins which can be raised to inoperative position very readily and locked in such position.

Another object of the invention is to provide cotton gins of this type with means for substantially counterbalancing the breast lift and other mechanism carried thereby in order to facilitate the raising of the breast manually whenever desired.

Other objects of the invention will become apparent as the detailed description thereof proceeds.

In the drawings:

Figure 1 is an end elevation of the right hand end of a double rib huller gin, with the cotton box in ginning position;

Figure 2 is a similar elevation of the same gin, with the cotton box in raised position;

Figure 3 is a broken front elevation of the said cotton gin, with parts omitted for clearness of disclosure; and

Figure 4 is a transverse vertical section taken on the line 4-4 of Figure 3.

As shown in the drawings, the cotton gin forming the present invention includes standards 1 and 2, forming the end supports for the gin mechanism. These standards are connected at the lower end in properly spaced apart positions by means of the angle iron 3; and are also connected at their upper ends by the angle iron 4 to which the cotton box is hingedly connected. Only one angle iron 3 is shown in the drawings, but it is to be understood that the other parts of the standards will be similarly secured to each other to form a rigid frame work.

The other ends 5 and 6 of the cotton box 7 are connected by a channel bar 8 which carries the rib bar and the cotton box and castings. In order to pivot the cotton box adjustably to the frame work of the gin, the castings which form the ends 5 and 6 of the cotton box have the trunnion members 9 and 10 suitably bolted thereto. As shown in Figure 3 of the drawings, each of the trun-

nion members 9 and 10 is recessed to fit tightly over the channel bar 8, and is secured thereto by means of the bolts 11 and 12.

The members 9 and 10 are provided with trunnions 13 and 14, respectively. These trunnions are mounted to rotate in apertures 15 and 16, formed in bearing members 17 and 18, respectively, which are suitably bolted or otherwise secured to the angle iron 4, as shown in Figures 1 and 3 of the drawings. The apertures 15 and 16 are of greater depth than the trunnions 13 and 14, and there is a slight space between each of the members 9 and 10, and the bearing members 17 and 18. This spacing is to permit the lateral adjustment of the cotton box as a whole along the axis of the trunnions 13 and 14.

To provide for the aforesaid lateral adjustment, the apertures 15 and 16 are centrally bored and screwthreaded to receive the adjusting screws 19 and 20 which are provided with lock nuts 21 and 22, respectively. It will be obvious from Figure 3 of the drawings that the end members 5 and 6, along with the cotton box supported thereby, can be adjusted to any desired position laterally of the gin frame work, and can be locked in this adjusted position by means of the lock nuts 21 and 22. This means that the entire cotton box can be adjusted to place the saws in the center of the spaces between the ribs, and can be locked in this position.

The huller roller shaft 23 is suitably journaled in bearings formed in the end castings 5 and 6; and this shaft projects through the casting 5 and has the driving pulley 24 keyed thereto or otherwise suitably secured thereto. The pulley 24 is driven by means of a belt 25 (see Figure 2) extending over idler pulleys 26 and 27, rotatably mounted on a bracket 27' secured to the angle iron 4, and around the pulley 28 suitably secured to the saw shaft 29.

The huller roller 30 is fixed to the shaft 23, within the gin box and is raised and lowered with the gin box by means of the lever 31 and linkage mechanism to be described hereinafter. The shaft 23 is also provided with a V-grooved braking pulley 32, secured to said shaft by means of a set screw 33 pass-

ing through a hub 34 formed on the braking pulley 32.

Immediately above the braking pulley 32, a brake shoe 35 is pivoted at one end of the casting 5, and has its lower edge curved to correspond with the curvature of the braking pulley 32. A short section 36 of braking material is shaped to fit the lower edge of the brake shoe 35, and is V-shaped in cross section to fit the V-shaped groove in the braking pulley 32. Preferably, the section 36 is made of such material as will frictionally grip the V-shaped periphery of the pulley 32 and bring it quickly to a stop.

15 An arm 37 extends downwardly from the casting 5 and has a laterally projecting lug 38 formed thereon. A tension spring 39 has one end hooked on to an eye 40 at the end of the lug 38, and has its other end hooked through an aperture 41 formed near the free end of the brake shoe 35. It will thus be apparent that the tension spring 39 normally holds the brake shoe 35 with its friction grip lining 36 in braking contact with the V-shaped groove of the pulley 32.

20 The other end casting 6 is similar in shape to the casting 5 and is provided with an arm 42 similar to the arm 37. A cross bar 43 connects the arms 37 and 42 to each other, and serves as part of a means for moving the cotton box to and from operative positions relative to the saws of the cotton gin. The movement referred to is effected by means of the handle 31 which is fixed to a squared end of a shaft 44, suitably journaled in the standards 1 and 2. The handle lever 31 is preferably fixed at the side of the gin opposite to that on which the braking mechanism for the huller roller is mounted. However, 25 it is immaterial which end of the gin it is mounted on so long as it is used in convenient position to rotate the shaft 44.

25 The shaft 44 has suitably secured thereto a bell crank 45 having the free end of one of its arms 46 connected to a strong tension spring 47, which has its other end hooked on to a lug 48 projecting from the framework. The other arm 49 of the bell crank 45 has its free end pivoted to a link 50 which 30 has its other end pivotally connected to a bracket 51 extending from a U-shaped plate 52 which straddles the cross bar 43 where it projects outwardly beyond the left hand end of the gin as shown in Figure 2.

35 The arm 49 is bifurcated where it receives the pivoted end of the link 50, the lower end of which is recessed to form a stop shoulder 53 adapted to contact with the rear edge of the arm 49 to limit the outward movement 40 of the linkage under the tension of the spring 47.

45 The tension spring 47 acts substantially as a counterbalance for the cotton box 7 and the mechanism carried thereby, in order to 50 relieve the operator from the manual exer-

tion in raising the heavy box without a counterbalance. It will be apparent from Figure 2 of the drawings that the arm 49 of the bell crank, and the link 50 connected to the end of this arm, constitute a toggle linkage for holding the cotton box locked in open position, as is common with all toggle linkages.

55 It will be apparent from Figure 2 of the drawing that when the cotton box 7 is in the open position shown therein, the spring 39 pulls the brake shoe 35 downwardly against the brake pulley 32. In order to release this brake shoe from braking contact with the pulley 32, the frame is provided with an edge 54 adapted to contact with the end 55 of the brake shoe, the said end being formed as a cam to slide on said edge 54 and raise the brake shoe away from the brake pulley 32 when the cotton box is lowered to the closing position shown in Figure 1.

60 The belt 25 and the pulley mechanism on which it operates are so designed that the belt is under tension only when the cotton box is in the closed position, shown in Figure 1. When the cotton box is moved away from this closed position, the tension on the belt slackens and the end 55 of the brake shoe 35 slides off the edge 54 on the frame and is pulled into braking position by means of the spring 39, thereby stopping the huller roller 30 from continuing its rotation and throwing cotton from the box.

65 A conveyor trough 56 extends directly below the huller roller 30 and is provided at its opposite ends with arms 57 and 58, suitably bolted to brackets 59 and 60, respectively, secured to the standards 1 and 2. An endless screw 61 is journaled in the trough 56 and serves to move hulls and foreign matter discharged from the cotton box along the trough 70 and to the end of the gin where it falls into a suitable receptacle onto an endless conveyor movable below the gin floor and under a battery of gins as is common in this art. The shaft 62 of screw 61 has a pulley 63 fixed thereto; and a belt 64 passing over pulley 63 and a pulley 64' on the saw shaft 29 serves to impart rotation from the saw shaft to the screw shaft 62.

75 The bottom of the trough 56 is perforated to form a screen through which cotton seeds, which are sometimes discharged with the hulls, are screened out and fall into a seed hopper 66 arranged directly below the conveyor hopper or trough 56.

80 What I claim is:

1. In a cotton gin, a frame having a cotton box pivoted thereto and normally held by gravity in operative position, arms projecting downwardly from said box, a cross bar connecting said arms, a shaft rotatable on said frame, a bell crank fixed to said shaft, a link pivoted at one end to an arm of said bell crank and at its other end to said cross bar, said link and arm being provided with co-

operating stop elements to limit the swing of said link in one direction around said arm, and a spring connecting the other end of said bell crank to said frame for substantially 5 counterbalancing said box.

2. In a cotton gin, a supporting frame, a cotton box pivoted to said frame to hang by gravity normally in operative position relative to the saws of the gin, a shaft journaled 10 in said frame, a lever for rotating said shaft, a bell crank fixed to said shaft, a link pivoted at one end to an arm of said bell crank and pivoted at its other end to said box, co-operative stop means on said link and arm to 15 limit the relative rotation of said link and arm in one direction, and yielding means connecting the other arm of said bell crank to said frame for substantially counterbalancing said box.

20 In testimony whereof I affix my signature.
JEFFREY JOHN WALLACE.
